EQUALIZING MECHANISM FOR BELT PRESSES OR THE LIKE

Carl F. Schnuck, New Haven, Conn., assignor to Farrel-Birmingham Company, Incorporated, Ansonia, Conn.

Application June 17, 1930. Serial No. 461,834

22 Claims. (Cl. 69—1)

This invention relates to equalizing devices, and while I have elected to illustrate and describe the invention with particular reference to an equalizing device for belt presses or the like, it will be understood that the invention may be applied to other machines where like or similar functions are desired.

In certain instances, machines such as belt presses comprise separate parts adapted for simultaneous movement, and it is desirable that the movements of these parts take place in a given relation, that is, that the movement of one part be substantially equal to or in a given ratio to the movement of the other. In the case of a belt press, such as herein illustrated, one of these parts is the pressing platen which usually is moved upwardly toward a cooperating platen to press the belt therebetween. At one end of the pressing mechanism there is arranged in ordinary practice a clamping device within which the belt is clamped so that it may be held in a stretched or taut condition during the pressing operation and upon the opposite side of the pressing mechanism is usually arranged a clamping and stretching device to clamp the end of the belt and stretch it to taut condition. In order that the pressing operation may be performed properly and efficiently, it is necessary, or at least desirable, that the clamping mechanism arranged at one side of the pressing device and the clamping and stretching mechanism arranged at the other side be maintained at substantially the horizontal level of the movable pressing platen.

Due to the fact that there is often more resistance to the movement of one of these parts than the other, or to other conditions obtaining in the operation of the machine, one of the parts will tend to move in advance of the other, and it is difficult, without the use of equalizing mechanism, to effect such movement of the various parts of the machine as will maintain them in proper relative positions.

One object of this invention, therefore, is the provision of an equalizing mechanism to insure proper relative movement of the movable parts of a machine such as a belt press or the like.

Another object of the invention is the provision of an equalizing mechanism designed to coordinate the movements of the movable parts of a belt press or like machine so that these parts will move simultaneously through substantially the same distances.

Another object of the invention is the provision in a belt press or like machine of an equal-

izing mechanism controlled by the movement of one of the movable parts of the machine and designed to control the amount of movement of another part of the machine.

More specifically the object of the invention is to coordinate the movement of the clamping and stretching means of a belt press or the like with the movement of the pressing platen, this coordination being effected by mechanism designed to control the application of power to the clamping and stretching mechanism and being in turn controlled by the movement of the pressing platen.

To these and other ends, the invention consists in the novel features and combinations of parts to be hereinafter described and claimed.

In the accompanying drawing:

Fig. 1 is a side elevational view partly in diagram of a belt press or the like to which my improved equalizing mechanism is applied, and

Fig. 2 is a sectional view of the fluid pressure valve employed therewith.

The belt press, which I have selected to illustrate and describe in order to exemplify one embodiment of my invention, comprises a base 10, upon which are supported a number of cylinders 11, having pistons 12 cooperating therewith, the pistons at their upper ends supporting the movable platen 13. It will, of course, be understood that the number of pistons and cylinders will be varied to suit the conditions obtaining in the particular machine. Above the platen 13 is a fixed platen 14, which may be suitably mounted so as to remain in a given position, it being understood that the belt or article to be pressed will be inserted between these two platens and will be subjected to pressure when the lower platen 13 is raised toward the upper fixed platen 14.

At one end of the pressing mechanism is a clamping device comprising a base 15, upon which are mounted suitable cylinders 16, having pistons 17 cooperating therewith and carrying at their upper ends a beam or support 18, for a clamping device shown more or less diagrammatically and comprising the clamping jaws 19 and 20. It will, of course, be understood that, in practice, means will be provided for effecting movement of these jaws toward and away from each other to clamp and release the belt, such means, however, forming no part of the present invention and hence not being illustrated herein.

At the opposite end of the machine is a clamping and stretching mechanism compris-

ing a base 21, cylinders 22, having pistons 23 cooperating therewith, the pistons carrying at their upper ends stretcher beams or supports 24. Means are provided for clamping the end of the belt to the stretching mechanism, this means being shown only diagrammatically and comprising the movable clamping jaws 25 and 26. These jaws will, like the jaws 19 and 20, be provided, in practice, with means to effect closing and opening movements thereof, and will also be provided with means by which they may be moved away from the pressing mechanism in order to stretch the belt to taut condition, this means comprising the cylinder 27 and piston 28.

15 It will be understood that the clamping jaws 19 and 20 at one side of the press and the jaws 25 and 26 upon the other side, will, when closed, be at substantially the level of the movable platen 13 and that, when the supports 18 and 20 24 are moved upwardly by the pistons attached thereto, the clamps will, of course, rise therewith. As has already been stated, it is essential that this upward movement of the clamping devices take place at substantially the same 25 time and that these movements be of the same magnitude as the upward movement of the platen 13.

To effect this end, I have provided means to control the application of the raising power to 30 the supports for the clamping devices by the movement of the movable platen. In the embodiment of my invention shown in the drawing, the pistons 17 and 23 are raised and lowered by the introduction and exhaust of pressure fluid into and from the cylinders 16 and 22. Leading to the cylinders 16 is a pipe or fluid conduit 30 connected by jointed sections 31 and 32 to a pipe 33 leading to the outlet port of a valve structure 34, and likewise the cylinders 22 are supplied from a pipe or fluid conduit 35 connected by jointed sections 36 and 37 to a pipe 38 leading to the outlet port of a valve structure 34^a.

The valve structures 34 and 34^a are mounted 45 upon a part of the machine that moves with the platen 13, being mounted as shown in the drawing at the upper end of one of the pistons 12, and the inlet ports of these valves are connected through jointed sections 39 and 40 to a 50 suitable source of fluid under pressure, which may be air, water, or other fluid as desired. As the valve structures 34 and 34^a are substantially alike, it will be necessary to describe only one thereof in detail. As illustrated in Fig. 2, each 55 of these valves comprises a housing 41 having valve stems 42 and 43 reciprocably mounted therein, which stems carry valves 44 and 45 co-operating respectively with valve seats 46 and 47, arranged in passages 48 and 49. The valves are held against their seats by suitable springs 50 and 51. An inlet port 52 is provided for the admission of pressure fluid into the passage 48 below the valve 44, and above this valve an outlet port 53 is provided which also communicates with the passage 48, and it will be understood that the pipe 33 (or pipe 38) leads into the outlet port 53 while the pipe 39 communicates with the inlet port 52.

70 Within the valve housing is a passage 54 leading from the passage 48 above the valve 44 to the passage 49 below the exhaust valve 45, and, above this exhaust valve, an exhaust port 55 communicates with the passage 49 and permits 75 the exhaust of pressure fluid from the valve.

At the upper end of the valve housing is pivotally mounted a rocker arm 56, controlled by a lever 57, it being understood that this rocker arm is adapted to engage and depress either the valve stem 42 or 43 and thus unseat the valves 44 or 45, or the rocker arm may remain in neutral position, as shown in Fig. 2, in which the valves are both held against their seats.

In order that these valves may be actuated by differential movement between the pressing platen on the one hand and the supports for the clamping devices on the other, rods 58 and 59 are connected each to one end of one of the arms 57. Walking beams 60 and 61 are connected at one end to the upper end of rods 58 and 59 respectively between buffer springs 62 and 63. The beam 60 is pivoted at an intermediate point 64, to an upright 65, secured at 66 to the movable platen, and at its other end is pivoted at 67 to an upright 68 secured at 69 to the movable support 24 for the clamping mechanism 25.

Likewise the walking beam 61 is pivoted at 70 to upright 71, secured at 72 to the press platen 13 and is also pivoted at 73 to upright 74, secured at 75 to the support 18 for the clamping mechanism 19 and 20.

Although it is not necessary in all aspects of the invention, it will be noted that the uprights 65 and 68 and also the uprights 71 and 74 are placed relatively close together with respect to the distances of the uprights 65 and 71 from the rods 58 and 59 respectively, so that any difference in movement between the uprights 65 and 68 or the uprights 71 and 74 will be multiplied at the ends of the walking beams connected to the rods 58 and 59, and will, therefore, promptly and effectively cause the arms 57 to be rocked in the proper direction by the rods 58 and 59, so as to open and close the proper valves.

The operation of my device is as follows:

If the parts are in the position shown in Fig. 1 and a belt is placed between the platens 13 and 14 and clamped in the clamping devices 19, 20 and 25, 26, and the belt is ready to be pressed, fluid pressure from any provided source (not shown) will be introduced into the cylinders 11 to raise the pistons 12 and thereby raise the platen 13. This will cause the uprights 65 and 71 to be raised with respect to the uprights 68 and 74 and will immediately cause the adjacent ends of the walking beams to rise and thereby move upwardly the rods 58 and 59. The upward movement of these rods will rock the valve levers 57 to the left, as shown in Fig. 2, depressing the valves 44. This will admit fluid pressure through the ports 52 into the passages 48 and permit it to pass outwardly through the outlet ports 53 to the cylinders 16 and 22, effecting the raising of the pistons 17 and 23 and likewise corresponding clamping mechanism. As long as the rods 58 and 59 are maintained in raised position, these conditions will obtain and the pistons 17 and 23 will continue to rise. If, however, the uprights 68 and 74 move upwardly to a greater extent than the platen 13, or than the uprights 65 and 71 connected thereto, the inner ends of the walking beams 60 and 61 will be depressed due to the rocking of these beams about 141 their pivots 64 and 70, and the arms 57 will thereupon be depressed to permit the valves 44 to close, and to open the valves 45, thus allowing the cylinders 16 and 22 to exhaust through the passages 49 and ports 55, and the upward move- 145

ment of the pistons 17 and 23 will be checked. With a proper setting of the valve structures 34 and 34^a and associated mechanism, the valves 44 and 45 will both be closed when the movable parts are in the desired relative position and will maintain this position of the parts until a differential movement thereof again effects the openings of the valves.

As illustrated the clamp supports 18 and 24 are moved by means of fluid operated devices comprising the cylinders 16 and 22 and the pistons 17 and 23. It will be obvious, however, that these supports may be moved by power means, for instance, such as electric motors, in which case the delivery of power to these motors would be controlled by rheostats which would be substituted for valves 34 and 34^a and which would be controlled by the rods 58 and 59.

While I have shown and described a preferred embodiment of my invention, it will be understood that it is not to be limited to all of the details shown, but is capable of modification and variation within the spirit of the invention and within the scope of the appended claims.

What I claim is:

1. In combination, a machine having two vertically movable parts, fluid pressure operated means to raise said parts, controlling means for varying the delivery of fluid pressure to the raising means for one of said parts, and said controlling means being in turn controlled by the movement of the other part.

2. In combination, a machine having a plurality of vertically movable members, individual power means for raising said members, one of which is operated by fluid pressure, and means actuated by the movement of one of said members to vary the delivery of fluid pressure to the means for raising another thereof.

3. A machine having a pair of vertically movable members, separate fluid pressure operated means to raise each of said members, and means for controlling the movement of one thereof by the movement of the other comprising controlling means to vary the fluid pressure delivered to the raising means for the first member and being in turn controlled by the movement of the second member.

4. A machine comprising a pair of members adapted to be raised in predetermined relation, individual means for raising each of said members, one of said means being operated by fluid pressure, and means controlled by one of said members to vary the delivery of fluid pressure to the raising means for the other of said members.

5. A machine having a pair of members adapted to be raised in a predetermined relation, individual means for raising each of said members, and means controlled by the first of said members to control the delivery of power to the raising means for the second of said members, said controlling means acting to raise said second member if the latter lags behind the first, and to lower said second member if the latter is in advance of the first.

6. A belt press or the like having a movable platen, and a movable clamping device, power means for moving each of said devices, and means to bring about a predetermined relation in said movement comprising control means to vary the power delivered to the raising means for the clamping device, and means actuated

by the movable platen for controlling said control means.

7. A belt press or the like having a movable platen and a movable clamping device, said devices being mounted for simultaneous movement in the same direction, power means to move said clamping device, and means controlled at least in part by said movable platen for controlling the delivery of power to said power means.

8. A belt press or the like comprising a movable platen and a movable clamping device, and means for effecting movement of said devices in a predetermined relation comprising power means for moving one of said devices, and means controlled by a differential movement of said devices to control the delivery of power to said power means.

9. A belt press or the like comprising a movable platen and a movable clamping device, and means for effecting movement of said devices in a predetermined relation comprising power means for moving one of said devices, and means controlled by a differential movement of said devices to control the delivery of power to said power means, said controlling means being mounted to move with one of said devices, and an actuating member therefor mounted to move with the other of said devices.

10. A belt press or the like having a movable platen and a movable clamping device, hydraulic means for moving said devices, and means for preserving a predetermined relation between the movements thereof, comprising means to control delivery of pressure fluid to the hydraulic means for one of said devices, and said control means being controlled by the differential movement of said devices.

11. A belt press or the like having a movable platen and a movable clamping device, hydraulic means for moving said devices, and means for preserving a predetermined relation between the movements thereof, comprising means to control delivery of pressure fluid to the hydraulic means for one of said devices, and said control means being mounted to move with one of said devices, and actuating means for said control means mounted to move with the other of said devices.

12. A press or the like having a movable platen and a movable clamping device, hydraulic means to move said devices, and means for preserving a predetermined relation between the movements thereof, comprising pressure fluid control means to control the delivery of pressure fluid to the moving means of one of said devices, said control means being mounted to move with the other of said devices, and actuating means for said pressure control means, said actuating means being controlled by differential movement of said devices.

13. A belt press or the like having a movable platen and a clamping device designed to move substantially in unison with the platen, hydraulic means to move each of said devices, and means to control the delivery of pressure fluid to the hydraulic moving means of the clamping device, said control means comprising a valve device mounted to move with the platen, and means connected with said movable clamping device to control the valve device.

14. A belt press or the like having a movable platen and a clamping device designed to move substantially in unison with the platen, hydraulic

means to move each of said devices, and means to control the delivery of pressure fluid to the hydraulic moving means of the clamping device, said control means comprising a valve device mounted to move with the platen, and means connected both with said clamping device and with said platen to control said valve device by the differential movement between the platen and clamping device.

10 15. A belt press or the like having a movable platen and a movable clamping device, and means to preserve a predetermined relation in the movement of said devices comprising a piston and cylinder to move the clamping device, 15 a valve device mounted to move with the platen to control the introduction of pressure fluid into and the release of pressure fluid from said cylinder, actuating means for said valve device, and means connected to said clamping device to 20 move said actuating means in a direction to admit pressure fluid to the cylinder when the clamping device lags behind the platen, and in a direction to release pressure fluid from the cylinder when the clamping device moves in 25 advance relation to the platen.

16. A belt press or the like comprising a movable platen, and a movable clamping device at each end of the platen, and means for effecting predetermined relative movements between the 30 platen and both clamping devices comprising power means to move said clamping devices, and means to control the delivery of power individually to said power means, said control means being in turn controlled by differential movement between the platen and the respective clamping device.

17. A belt press or the like having a movable platen and a movable clamping device, and means for effecting a predetermined relative movement of said devices comprising power means to move said clamping device, control means for controlling the delivery of power to said power means, said control means being mounted to move with the platen, and a lever 45 pivotally connected to said clamping device and to said platen to actuate said control means.

18. A belt press or the like having a movable platen and a movable clamping device, and means for effecting a predetermined relative movement of said devices comprising power means to move said clamping device, control means for controlling the delivery of power to said power means, said control means being mounted to move with the platen, and a lever 50

55 pivotally connected to said clamping device and to said platen to actuate said control means, said power means comprising a piston and cylinder, and said control means comprising a valve to control the delivery of pressure fluid to the cylinder.

80 19. A belt press or the like having a movable platen and a movable clamping device, and means for effecting a predetermined relative movement of said devices comprising power means to move said clamping device, control means for controlling the delivery of power to said power means, said control means being mounted to move with the platen, and a lever 85 pivotally connected to said clamping device and to said platen to actuate said control means, said power means comprising a piston and cylinder, and said control means comprising a valve to control the delivery of pressure fluid to the cylinder.

90 20. A belt press or the like comprising a movable platen, and a movable clamping device at each end of the platen, and means for effecting predetermined relative movements between the 95 platen and both clamping devices comprising individual power means for moving each of said clamping devices, and control means individual to each of said power means to control the delivery of power thereto, each of said control means having parts connected to the platen and the respective clamping device to be controlled by differential movement between the platen and the respective clamping device.

100 21. A machine having a pair of movable members and means for effecting movement of said members in a predetermined relation, comprising fluid pressure operated means for moving one of said members, and means controlled by a differential movement of said members to control the delivery of fluid pressure to said fluid pressure operated means to maintain them in said predetermined relation.

110 22. A machine having a pair of members adapted for movement in the same direction, and means for effecting a predetermined relative movement of said members comprising fluid pressure operated means for moving one of said members and means controlled by a differential movement of the members to vary the delivery 115 of fluid pressure to said moving means, said controlling means being mounted to move with one of said members.
